Attorney
Inventor
William C. Jones
Prindle, Wright, Heath & Bean.

UNITED STATES PATENT OFFICE.

WILLIAM C. JONES, OF NIANTIC, ILLINOIS.

MOLDING FLASK.

Application filed April 10, 1925. Serial No. 22,042.

To all whom it may concern:

Be it known that I, WILLIAM C. JONES, a citizen of the United States, a resident of Niantic, in the county of Macon and State 5 of Illinois, have invented certain new and useful Improvements in Molding Flasks, of which the following is a specification.

This invention relates to improvements in molding flasks having particular relation to 10 the hinge and pin construction of the same whereby the separable parts of a molding flask may be readily assembled or fit together and disassembled or taken apart.

The object of this invention is the provision of a device of this character which involves the elements of simplicity in operation and construction as well as accuracy. Various other objects and advantages will appear from the following specification.

20 To the accomplishment of the foregoing and such other objects as may hereinafter appear my invention consists in the construction, combination and arrangement of parts hereinafter described and then sought 25 to be defined in the appended claims, reference being had to the accompanying drawings forming a part hereof and which show for the purpose of illustrative disclosure one form of my invention and also a modified form of my invention, it being expressly understood, however, that various changes may be made in practice within the scope of the claims without digressing from my inventive idea.

35 Figure 1 is a perspective view of a molding flask provided with a hinge construction embodying my invention, the parts being shown in closed position.

Figure 2 is a transverse cross section of 40 the construction shown in Figure 1 taken substantially on line 2—2 of Figure 1, the parts, however, being shown in open position.

Figure 3 is a perspective view of the two 45 parts of the hinge construction or pin shown in Figures 1 and 2.

Figure 4 is a perspective view of one end 50 of a molding flask having a modified form of connection also embodying my invention.

Referring now to the drawings the numeral 1 designates one part of a separable molding flask and the numeral 2 the other part thereof. No novelty is claimed for 55 the flask itself and, therefore, this may be

of any suitable construction. In the preferred form illustrated the hinge includes two parts which are designated 3 and 4 respectively, 3 being the upper part of the hinge and 4 being the lower. This lower 60 part of the hinge has the face or securing plate 5 and projecting therefrom is provided a pair of brackets 6. The top of these brackets is in line with the top of the face or securing plate 5 and they are provided 65 along their top each with a groove or recess 7 which is in alignment with the groove or recess in the other bracket.

The upper member of the hinge is likewise formed with the face or securing plate 70 8 and is further provided with the outwardly and downwardly extending hinge lug 9, the major portion of which is rounded as shown but having the flat face 10 extending from the junction of the lug 9 with the 75 face or securing plate 8. The purpose of this flat portion 10 of the lug is to align and hold the two parts of the hinge and the flask properly and to accomplish that it bears against the front part of the face 80 or securing plate 5 of the lower hinge member, when the two parts of the flask are in assembled relation. The hinge pin 11 is passed through or otherwise secured to the hinge lug 9 and projects on either side 85 thereof as shown so as to fit within the aligned grooves or recesses 7 of the hinge brackets, it being understood that the hinge lug 9 fits between said hinge brackets. It is also to be noted that when the hinge is 90 thrown to its open position the ends 12 of the hinge brackets 6 will come into engagement with the front face of the face or securing plate 8, causing the same to pivot thereon and to lift the hinge lug 9 and the 95 hinge pin 11 out of engagement with the hinge brackets 6 and the grooves or recesses 7 therein. In that aspect the hinge is automatic in its throw-out function.

I have described one hinge only, it being 100 understood and as shown in the drawings that a plurality of the hinges are utilized on each side of the parts of the molding flask and that in view of their separable construction either side may be opened using 105 the other side as the hinge and the hinge operation as well as the throw-out function will be obtained just the same. This is also true regardless of which part of the hinge is used as the top and which as the lower ele- 110

ment, the hinge in this aspect being completely reversible.

In the event it is not necessary or desirable to use a pivot hinge construction, substantially the same construction may be utilized to give a sliding locking arrangement to the two parts of the flask. This is illustrated in Figure 4 of the drawing. In this figure the two parts of the flask are designated 13 and 14 and the lower part of the flask 14 has a plurality of hinge members 15 secured thereto, these hinge members being the same in construction as the lower hinge member 4 previously described. The upper member 15' of the locking construction is the only one which differs. This includes the face or supporting plate 16 having a lug 17 projecting centrally and downwardly therefrom, this lug corresponding to some extent to the hinge lug 9 previously described. It is provided with the locking pin 18 which is adapted to rest in the aligned grooves or recesses of the hinge brackets of the lower member, but the end thereof instead of being rounded to permit a pivotal hinge movement is extended a considerable distance downward as at 19 and provided with the corresponding flat inner face 20 which bears against the outer face of the face or securing plate of the lower member, fitting between the two brackets of the lower member. This, therefore, functions as a guide in assembling the two parts of the flask and means for holding them securely together in proper alignment and also as a guide in separating the two parts of the flask, in that the movements of the parts in separating are guided for a sufficient distance to clear the pattern. The two parts are very securely held in proper position with the manifest advantage that they may be readily and quickly separated without interfering with the contents of the flask.

What I claim is:

1. A molding flask composed of two separable parts, securing and aligning means on a plurality of the sides thereof to hold the two parts in proper alignment when assembled, said securing and aligning means including one member having a pair of outwardly extending brackets provided with aligning grooves or recesses in their upper face and the other of said members having a lug projecting outwardly and downwardly and adapted to be positioned between said brackets, said lug being provided with a pin to fit in the grooves or recesses in said brackets, said lug also being formed with a flat face adapted to engage and bear against the front face of the other aligning and securing member.

2. A molding flask composed of two parts separable from each other, aligning and securing members provided on a plurality of sides thereof so as to hold the two parts in

proper alignment when assembled and permitting the separating of the two parts, one of said aligning and securing members having a pair of brackets extending outwardly therefrom provided with aligning recesses or grooves in their upper face, the other of said members having an outwardly and downwardly projecting lug adapted to be positioned between said brackets, said lug also having a pin adapted to fit in said grooves or recesses whereby the two parts of said aligning and securing members are hingedly connected together, the ends of said brackets being adapted to engage the other aligning and securing member at the end of the opening movement to throw the lug and its pin out of position and engagement with the grooves or recesses in said brackets.

3. A molding flask composed of two parts separable from each other, aligning and securing members provided on a plurality of sides thereof so as to hold the two parts in proper alignment when assembled and permitting the separating of the two parts, one of said aligning and securing members having a pair of brackets extending outwardly therefrom provided with aligning recesses or grooves in their upper face, the other of said members having an outwardly and downwardly projecting lug adapted to be positioned between said brackets, said lug also having a pin adapted to fit in said grooves or recesses whereby the two parts of said aligning and securing members are hingedly connected together, the ends of said brackets being adapted to engage the other aligning and securing member at the end of the opening movement to throw the lug and its pin out of position and engagement with the grooves or recesses in said brackets, said lug also having a straight face adapted to engage with the face of the other aligning and securing member when the parts are in closed position.

4. A hinge construction including a pair of separable parts, one part having a plurality of outwardly extending brackets spaced apart and each provided with a groove or recess, the other part of said hinge construction having an outwardly and downwardly extending lug adapted to fit between said brackets, said lug being provided with a pin construction adapted to rest in said grooves or recesses and form the pivot or pintle for the hinge, said lug having a straight face adapted to engage with the face of the other part of the hinge construction between said brackets.

5. A hinge construction including a pair of separable parts, one part having a pair of outwardly extending brackets spaced apart and each provided with a groove or recess in alignment with the groove or recess of the other, the other part having an out-

wardly and downwardly extending lug adapted to fit between said brackets and provided with a pin adapted to rest in said grooves or recesses and form the pivot or pintle for the hinge, the ends of said brackets being adapted to engage the other part at the end of the opening movement so as to throw the lug and its pin out of position and engagement with said grooves or recesses.

6. A hinge construction including a pair of separable parts, one part having a pair of outwardly extending brackets spaced apart and each provided with a groove or recess 15 in alignment with the groove or recess of the other, the other part having an outwardly and downwardly extending lug adapted to fit between said brackets and provided with a pin adapted to rest in said grooves or recesses and form the pivot or pintle for the hinge, the ends of said brackets being adapted to engage the other part at the end of the opening movement so as to throw the lug and its pin out of position 25 and engagement with said grooves or recesses, said lug having a flat face portion

adapted to bear against the flat face portion on the other part of said hinge construction.

7. An aligning and securing construction 30 for molding flasks including a pair of members adapted to be secured to the separable parts of the flask, one of said members having a pair of brackets spaced apart and extending outwardly from the base thereof, 35 said member having a flat surface between said brackets, each bracket being provided with a groove or recess, the other of said members having an outwardly and downwardly projecting lug adapted to fit between 40 said brackets and provided with a pin construction adapted to rest in said grooves or recesses when the parts of the flask are in assembled relation, said lug having its inner or front face flattened so as to bear against 45 said flat surface of the other member when the parts are assembled so as to hold the two members in alignment.

In testimony that I claim the foregoing, I have hereunto set my hand this 28th day of 50 February, 1925.

WILLIAM C. JONES.
